(57) **CLAIM**

I claim the ornamental design for a three-legged circular table, as shown and described.

DESCRIPTION

FIG. 1 is a perspective view of said three-legged circular table;

FIG. 2 is a front view thereof;

FIG. 3 is a perspective view of one of the joints thereof;

FIG. 4 is a frontal view of the interior of one of the joints thereof;

FIG. 5 is a bottom plan view thereof; and,

FIG. 6 is a top plan view thereof.
